STRIP BURSTER

John T. Davidson, Dayton, Ohio, assignor to The Standard Register Company, Dayton, Ohio, a corporation of Ohio

Application October 3, 1942, Serial No. 460,657

18 Claims. (Cl. 164—84.5)

This invention pertains to strip or web feeding and severing apparatus, by which a continuous strip of material is automatically divided at predetermined longitudinally spaced intervals into a succession of individual sheets, and more particularly to intermittent strip tensioning mechanism, whereby successively advanced terminal portions of the strip are tensioned beyond the tensile strength of transverse weakened division lines within such advanced portions, and thereby progressively detached from the supply portion of the strip or web.

It is quite common commercial practice to inscribe continuous series connected printed forms, such as checks, utility bills, invoices, statements and other record sheets while intact, by passing such strips either singly or in multiple, with interleaved transfer material, through a writing or imprinting machine. Subsequently, the strips are divided between successive inscribed forms into individual sheets. To facilitate separation, the record strip is provided with longitudinally spaced transverse weakened division lines, upon which the strip is bursted by being subjected to excessive longitudinal pulling strain, as the line containing area reaches severing position.

Simultaneously with the advancement of the strip relative to the severing or bursting position, the margins thereof are automatically trimmed to remove marginal configurations or feed band areas engaged by strip feeding devices, which serve to control and time the advancement of the strip in synchronism with the strip severing operations. The rate of advancement of the strip relative to the rate of operation of the tensioning devices may be varied to enable the strip to be uniformly divided into sheets of different length in accordance with closely or more distantly spaced transverse weakened division lines thereof.

The present disclosure is a further development and improvement upon the construction shown in the copending application of Ratchford and Lee, Serial No. 361,406, filed October 16, 1940, now matured into Letters Patent No. 2,328,592 of Sept. 7, 1943.

The object of the invention is to improve the construction as well as the means and mode of operation of strip feeding and severing machines, whereby they may not only be economically manufactured and operated, but will be more efficient in use, automatic in operation, uniform in action, of simplified form, having relatively few parts, and be unlikely to get out of repair.

A further object of the invention is to provide

an apparatus of compact form and possessing minimum power requirement for its operation.

A further object of the invention is to enable the advancement of the strip to be properly synchronized with the strip bursting devices and to enable a continuous strip of material to be accurately divided into uniform sheets of greater or less length.

A further object of the invention is to provide strip tensioning mechanism by which the advanced terminal portion of the strip is momentarily subjected to accelerated advancement while the trailing portion of the strip is simultaneously snubbed or retarded in opposition to the accelerated feeding influence, thus subjecting a transverse weakened line of the strip intermediate the points of accelerating and retarding influence to excessive tension and bursting strain.

A further object of the invention is to provide combined strip trimming and severing devices operating harmoniously in continuous sequence.

A further object of the invention is to provide adjusting means by which accuracy and certainty of operation are assured.

A further object of the invention is to provide a strip feeding and bursting machine having the advantageous structural features and inherent meritorious characteristics and mode of operation herein set forth.

With the above primary and other incidental objects in view as will more fully appear in the specification, the invention intended to be protected by Letters Patent consists of the features of construction, the parts and combinations thereof, and the mode of operation, or their equivalents, as hereinafter described or illustrated in the accompanying drawings.

In the drawings, wherein is shown the preferred but obviously not necessarily the only form of embodiment of the invention,

Fig. 1 is a front elevation of the assembled machine viewed from the right of Figs. 2, 4 and 5.

Fig. 2 is an end elevation of the machine showing a portion of the driving train viewed from the left of Fig. 1.

Fig. 3 is an end elevation, partly broken away, opposite that of Fig. 2, as viewed from the right of Fig. 1.

Fig. 4 is a vertical sectional view of the feeding and bursting mechanism during the interim period between bursting operations while the strip is being freely advanced.

Fig. 5 is a view similar to that of Fig. 4 at the moment of bursting operation.

Figs. 6 and 7 are detail sectional views.

Fig. 8 illustrates a disc for forming a longitudinal weakened line upon which the marginal portion of the strip is subsequently separable.

Fig. 9 is a fragmentary view of a portion of the record strip provided with a weakened division line.

Like parts are indicated by similar characters of reference throughout the several views.

The present bursting machine is of relatively small size and compact form adapted to be supported in elevated position on a table or stand. The frame of the apparatus comprises relatively spaced upright end plates 1 and 2 supported upon a base 3 and interconnected by tie rods 4.

The driving gear trains beyond the end plates 1 and 2 are enclosed and protected by casing or housing portions 5, which continue at 5' at the front and rear of the frame and enclose the driving motor 6. The operating mechanism by which the strip or web is advanced and tensioned to the bursting point is exposed between the end plates. This mechanism includes a pair of frictional feeding and snubbing rollers 7 and 8 and a pair of frictional tensioning or snatch rollers 9 and 10. At least one of the latter is driven at a greater peripheral speed than the snubbing rollers 7 and 8. The rollers 7 and 8 are rubber covered, or of analogous material, having a tenacious strip engaging surface, and preferably comprise a plurality of axially adjustable relatively spaced rubber collars or rings mounted on corresponding shafts 11 and 12. The corresponding frictional rollers 9 and 10 are preferably metallic rollers having knurled surfaces, but may also be of rubber or the like. The strip engaging collars of the roller 8 are mounted for axial adjustment to and fro upon a common shaft 13, while the rollers 10 preferably, but not necessarily, comprise integral knurled raised areas on the shaft 14.

A strip feeding pin wheel 15, engageable in longitudinally spaced holes or other configurations in the strip or web, is mounted concentrically with the snubbing rollers 8 upon the common shaft 13. The pin wheel 15 maintains constant feeding engagement with the strip, whereas the rollers 7-8 and 9-10 engage therewith only intermittently. As a result, the rollers 7-8 operate conjointly with the pin wheel to impart movement and control the advancement of the strip during a part of the cycle of operation, during the remainder of which the strip is advanced by the pin wheel 15 alone independently of the friction rollers 7 and 8.

To enable the vibratory movement of the snubbing and snatch rollers 8 and 10 toward and from the corresponding rollers 7 and 9, the shafts 11 and 12 for the latter are journaled in the side frames 1 and 2 for rotation on fixed axes, while the roller shafts 13 and 14 of the matching rollers 8 and 10 are mounted for bodily movement relative to the shafts 11 and 12 and the rollers carried thereby.

Pivottally mounted on a transverse shaft 16 supported in the side plates 1 and 2 is a pair of oscillatory arms 17 in which the roller shafts 13 and 14 are journaled. The rock arms 17 are actuated in timed sequence with the advancement of the strip to momentarily grip the strip between the respective pairs of rollers 7-8 and 9-10 by rotary cams 18 carried upon a revoluble cam shaft 19 journaled in the end plates of the frame, and having operative engagement upon each rotation with rollers 20 mounted upon the respective oscillatory mounting arms 17.

The rollers and pin wheels are actuated by the driving motor 6 which is connected by a belt 21

with a combined pulley and hand wheel 22 mounted upon an extension of the shaft 12 of the fast rotating tensioning or snatch roller 9 outside the frame end 1.

5 The shaft extension carries a gear pinion 23 behind the pulley 22 which meshes with the larger of a pair of inter-connected concentric idler gears 24, the smaller member 25 of which meshes with a gear pinion 26 upon the extremity of the snubbing roller shaft 11. The ratio of the several gears is such that the snubbing roller 7 is driven at a peripheral speed materially less than that of the tensioning or snatch roller 9. The roller 10 and shaft 14 are preferably loose and rotate idly under friction driving influence of the roller 9 and the strip therebetween.

10 The snubbing roller shaft 11 carries at its opposite end beyond the end frame plate 2 a pair of gear pinions 27 and 28. The pinion 27 of lesser pitch intermeshes with a large idler gear 29 mounted on an adjustable arm 30 which is pivoted upon the extension of the shaft 14 concentric with the gear pinions 27 and 28. The swinging arm 30 carrying the gear 29 is adjustable to and fro within the limits of a concentric arcuate slot 31 in the end plate, and is secured in adjusted position by a clamp bolt 32 in the swinging arm engaging in such slot.

15 By adjustment of the swinging arm 30 the large idler gear may be made to intermesh with any one of a plurality of interchangeable gear pinions 33 of different size mounted on the extremity of the cam shaft 19. By interchanging other gears 33 of larger or smaller size, the cam shaft is made to rotate faster or slower, and the timing of the mounting arm oscillations is correspondingly changed to permit greater or less lengths of the strip material to be advanced during the periods between succeeding engagements of the rollers 40 therewith to effect the strip severing operations. This accommodates strips or webs having differently spaced transverse weakened lines, and enables uniform severance thereof into sheets of greater or less length, according to the relative spacing of the division lines. The gear pinion 28 upon the extremity of the snubbing roller shaft 11 meshes with a corresponding gear pinion 34 upon the extremity of the lower snubbing roller shaft 13, which shaft also carries the strip feeding pin wheels 15. Inasmuch as the shaft 13 and gear 34 are movable through a very short range toward and from the shaft 11 and intermeshing gear 28 in unison with the vibration of the oscillatory mounting arms 17, the intermeshing gears 45 28 and 34 are of somewhat greater pitch than the gear 27, and their teeth are elongated sufficiently to maintain their intermeshing relation throughout the range of such relative movement. The rotation of the shaft 11 and gear 28 thereon thus transmits continuous rotary motion to the shaft 13 and the pin wheels 15 mounted thereon notwithstanding the vibratory motion of the shaft 13 and gear 34. Upon approach of the shafts 11 and 13 and the rollers 7-8 carried thereby, the pin wheels are shifted in unison therewith while maintaining their feeding engagement with the strip. As the rollers 7-8 impinge upon the interposed web or strip, they impart thereto by frictional engagement a forward feeding action in unison with the feeding influence of the strip engaging pin wheels 15.

50 However, upon retraction of the arms 17 and therewith the shaft 13 and roller 8, the pin wheels continue to advance the web or strip. During the 55 interval between engagements of the strip be- 60

65 70 75

tween opposing rollers, the terminal portion of the strip will have been advanced by the pin wheels a sufficient distance to thrust the free end of the strip between the then separated tensioning rollers 9 and 10, and to position a transverse weakened line upon which the strip or web is to be severed intermediate the pairs of rollers 7-8 and 9-10. Upon elevation of the oscillatory arms 17 by the cams 18, the strip will be simultaneously grasped between the respective pairs of rollers 7-8 and 9-10 which rotate at different rates of peripheral speed. The snatch rollers 9-10 being more rapidly rotated than the snubbing rollers 7-8 will impose a strong longitudinal pulling strain upon the strip which is resisted by the more slowly rotating snubbing rollers 7-8, whereby the strip is subjected to tensioning influence in excess of the tensile strength of the strip coincident with the transverse weakened division line then positioned between the pairs of rollers. At the same time, the strip will be advanced by the snubbing rollers in unison with its advancement by the pin wheels 15, so that the timing of the strip is maintained and the pin wheels are protected and relieved of the strain of the tensioning by the snatch rollers 9-10. The strip fails coincident with the transverse weakened line under the excessive tension imposed thereon and the separated terminal portion is discharged by continued rotation of the rollers 9-10 and the momentum of the severed sheet into the sheet receiver 35.

Guide fingers 36 adjustably mounted on a transverse rod 4' maintain the advancing strip in feeding engagement with the pin wheels 15. The latter are axially adjustable upon the shaft 13 to accommodate strips or webs of different widths.

As the web or strip is advanced, the marginal configurations or feed bands are trimmed off by severing discs 38 which coact with the peripheries of the pin wheels 15 in offset relation with the line of feeding pins. The trimmer discs may be sharp and operate to shear the strips, or may be dull, in which event they serve to break the strip on longitudinal preweakened division lines. The trimmer discs 38 are carried by arms 39 secured to the shaft 16, upon which the oscillatory mounting arms 17 are pivoted. The shaft 16 is mounted in the end plates 1 and 2 for rocking motion. It is provided at one extremity with a crank arm 40 carrying a spring actuated locking plunger 41, upon disengagement of which the shaft 16 may be rocked by the crank to lift the arms 39 and remove the trimmer discs from strip severing relation with the pin wheels to facilitate introduction of a new strip or web to be trimmed and severed.

To enable relative adjustment of the opposing snubbing and tensioning rollers, as may be necessary to achieve proper cooperation therebetween, the axis of oscillation of the vibratory mounting arms 17 may be shifted laterally or vertically within limited range. To this end, the rock shaft 16 is journaled in eccentric bushings or bearing sleeves 42 (Fig. 7), having a marginally notched flange 43, and locked in selected positions of rotative adjustment by engagement of a locking screw 44 in one or another of the marginal notches. By such rotative adjustment of the eccentric bearing, the positions of the vibratory arms 17 may be slightly varied to bring the opposing rollers of the respective pairs into proper degree of gripping relation with the strip and in adjusted relation with each other. Similar eccentric rotatively adjustable mountings 45 are

provided for the rollers 20 upon the vibratory arms 17 to vary the response of the arms to the action of the rotary cams 18.

A table 46 intermediate the respective pairs of rollers temporarily supports the severed portion of the strip and guides the terminal edge of the supply strip between the tensioning rollers after each severing operation. The rear wall of the receiving compartment extends at 47 into adjacent relation with the tensioning rollers to receive the severed portions of the strip therefrom and guide them into the receiving compartment. The driving motor 6 is mounted upon an oscillatory shelf 48 pivoted at 50 to the main frame, whereby the deflection of the mounting shelf under the weight of the motor serves as a belt tightener to keep the drive belt 21 under proper driving tension.

In Fig. 8 there is shown a marginally serrated disc 51 for perforating or otherwise weakening the strip on a longitudinal line 52 to enable subsequent separation of the marginal feed band, in lieu of shearing or trimming the strips by the disc 38 as they pass through the machine. Such temporary retention of the punched marginal portion on the severed sheets is desirable when the sheets are to be subsequently collated in predetermined relation, as for example, upon a peg board or when the holes are to be temporarily employed for binding purposes.

Fig. 9 illustrates a portion of the strip provided with such weakened line, and the marginal area partially separated.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific features shown, but that the means and construction herein disclosed comprise the preferred form of several modes of putting the invention into effect, and the invention is therefore claimed in any of its forms or modifications within the legitimate and valid scope of the appended claims.

Having thus described my invention, I claim:

1. A strip severing apparatus for progressively dividing a continuous strip of material into a succession of individual sheets upon longitudinally spaced transverse weakened division lines by subjecting succeeding terminal portions of the strip to longitudinal pulling strain in excess of the tensile strength of the strip coincident with such weakened lines, including two pairs of relatively spaced rollers having intermittent gripping engagement with the strip at opposite sides of a transverse weakened line thereof, one roller of each pair being movable simultaneously into cooperative relation with the opposing rollers of the respective pairs at timed intervals, driving mechanism for actuating the respective pairs of rollers at different peripheral speeds, a strip feeding device mounted concentrically with one of said movable rollers for advancing the strip predetermined distances intermediate succeeding strip gripping operations of the rollers to position a transverse weakened division line of the strip between the respective pairs of rollers, and operat-

ing means for intermittently moving one roller of each pair of rollers into cooperative relation with the opposing rollers of the respective pairs in synchronism with the advancement of the strip.

2. A strip severing apparatus for progressively dividing a continuous strip of material into a succession of individual sheets upon longitudinally spaced transverse weakened division lines by subjecting succeeding terminal portions of the strip to longitudinal pulling strain in excess of the tensile strength of the strip coincident with such weakened lines, including a main frame, a pair of relatively spaced rollers mounted in the main frame for rotation on fixed axes, a vibratory frame pivoted to the main frame, a pair of relatively spaced rollers carried by the vibratory frame and movable therewith into and out of cooperative relation with the first mentioned pair of rollers to intermittently grip a strip of material to be severed therebetween, motion transmitting means for rotating at least two of the relatively spaced rollers at a different peripheral speed, a strip feeding device for advancing a strip to be severed relative to the said rollers, and operating means for vibrating the pivotally mounted roller carrying frame in timed relation with advancement of the strip to intermittently simultaneously grip the strip at opposite sides of a transverse weakened line between relatively spaced rollers rotating at different peripheral speeds.

3. A strip severing apparatus for progressively dividing a continuous strip of material into a succession of individual sheets upon longitudinally spaced transverse weakened division lines by subjecting succeeding terminal portions of the strip to longitudinal pulling strain in excess of the tensile strength of the strip coincident with such weakened lines, including a pair of tensioning rollers and a pair of snubbing rollers rotating at different peripheral speeds, strip feeding means for advancing the strip in synchronism with the rotation of the rollers to position a transverse weakened line of the strip intermediate the respective pairs of rollers preparatory to succeeding strip gripping actions thereof, and common operating means for intermittently shifting the strip feeding means and the rollers of the respective pairs toward and from coacting rollers of the pairs to simultaneously grip an intermediate strip of material at opposite sides of a transverse weakened line thereof.

4. A strip severing apparatus, wherein successively advanced terminal portions of a continuous strip of material are intermittently tensioned beyond the tensile strength of transverse weakened division lines within such advanced positions and thereby bursted into individual sheets, including a pair of relatively spaced rollers rotating at different peripheral speeds, a vibratory frame, a pair of correspondingly spaced rollers carried thereby for intermittent gripping engagement with a continuous strip of material advanced therebetween to tension an intermediate portion of the engaged strip, and driving means for imparting different peripheral speeds to mating rollers of the assembly and for oscillating the vibratory frame.

5. A strip severing apparatus, wherein a continuous strip of material is progressively transversely severed at longitudinally spaced intervals into a succession of individual sheets, including a strip severing device, dual frictional and pin type strip feeding devices, a vibratory frame upon which the dual strip feeding devices are mounted,

and means for actuating the frame in timed relation with the advancement of the strip, the construction and arrangement being such that the dual strip feeding devices have simultaneous feeding engagement with the strip during a part of the cycle of operation, one of said strip feeding devices having operative feeding engagement with the strip to the exclusion of the other strip feeding device during the remainder of the cycle of operation.

6. In a strip feeding device for advancing a continuous strip of material, a rotary shaft, a pin wheel continuously engageable in longitudinally spaced configurations of the strip, and a frictional roller intermittently engageable with the strip mounted in concentric relation upon the rotary shaft for intermittent simultaneous feeding engagement with the strip.

7. A strip feeding device for advancing a continuous strip of material, including a pin wheel operatively engaged with the strip and a frictional roller concentrically positioned therewith for intermittent engagement with the strip.

8. A strip feeding device for advancing a continuous strip of material, including a pin wheel and a frictional roller concentrically positioned for simultaneous operative feeding engagement with the strip, and a member with which the friction roller intermittently cooperates to impart advance motion to a strip of material concurrently with its advancement by the pin wheel, the latter being effective to advance the strip during non-strip feeding periods of the roller.

9. A strip feeding and severing apparatus for progressively transversely dividing a continuous strip of material into a succession of individual sheets, including a strip severing device and a strip snubbing device intermittently engageable with a strip of material, and a strip feeding device mounted for alternating movement in timed relation with the intermittent engagement of the severing and snubbing devices with the strip while said feeding device maintains its engagement therewith.

10. A strip separating apparatus, including a pair of rollers mounted for rotation on fixed axes and revoluble at different peripheral speeds, a second pair of rollers cooperating respectively with the rollers of the first mentioned pair, strip feeding means for advancing intermediate the pairs of rollers a strip of material having transverse longitudinally spaced weakened lines therein, a vibratory carrier for the strip feeding means and the rollers of the second pair intermittently shifting the rollers of one pair into strip engaging relation with the rollers of the other pair, and actuating means for driving the rollers and strip feeding means and vibrating the carrier in timed sequence.

11. A strip separating apparatus, including two pairs of strip engaging rollers, the rollers of the respective pairs being revoluble at different peripheral speeds, one roller of each pair being bodily movable toward and from the companion roller thereof into and out of strip engaging relation, control means for effecting simultaneous relative movement of the rollers of the respective pairs toward and from each other, and strip feeding means bodily movable in unison with the to and fro movement of the rollers for advancing a strip of material having longitudinally spaced transverse weakened division lines, intermediate the rollers, and driving means for rotating the respective pairs of rollers at different peripheral speeds and changing the relation of the rolls of

each pair into and out of unison engagement with the strip simultaneously with the advancement of the strip relative thereto.

12. A strip separating apparatus, including strip severing means for transversely dividing a continuous strip of material at predetermined longitudinally spaced intervals, including a friction roller intermittently engageable with the strip for advancing the strip to the severing device and resisting accelerated advancement thereof, and a pin wheel mounted concentric with the said friction roller for unison rotation having feeding engagement with the strip simultaneously with its engagement by the friction roller and maintaining its feeding engagement therewith during interim periods between successive intermittent periods of engagement of the roller therewith.

13. A strip separating apparatus, including strip severing means for transversely dividing a continuous strip of material at longitudinally spaced intervals, including a vibratory friction roller intermittently bodily movable into and out of engagement with the strip for advancing the strip to the severing device and resisting accelerated movement thereof, a pin wheel mounted concentrically with the friction roller for unison rotation and bodily movable therewith, said pin wheel maintaining constant engagement with the strip during vibratory movement of the roller to advance the strip conjointly with the roller during engagement of the latter with the strip and independently thereof during interim periods between succeeding periods of intermittent engagement of the roller with the strip.

14. As an article of manufacture, a revoluble friction roller for intermittent frictional feeding engagement with a continuous strip of material and a pin wheel mounted concentric with the roller for unison rotation therewith and having continuous feeding engagement with the same strip of material.

15. A strip severing apparatus, including strip tensioning device intermittently engageable with the strip to exert pulling influence thereon in excess of the tensile strength of a transverse weakened division line thereof, a pair of snubbing rollers, at least one of which is bodily movable relative to the other to engage the strip and resist the pulling influence of the tensioning device simultaneously with the exertion of such tensioning influence, a bodily movable strip feeding de-

vice for advancing the strip at a speed substantially equal to the peripheral speed of the snubbing rollers and movable in unison therewith, and driving means for actuating the tensioning device, the strip feeding device and the snubbing rollers in synchronism.

16. A strip severing device, including a pair of strip tensioning rollers and a relatively spaced pair of strip snubbing rollers, a vibratory carrier upon which one roller of each pair is mounted for simultaneous intermittent movement toward and from the other member of the respective pairs of rollers to momentarily grip a strip to be severed therebetween, a strip feeding device mounted 10 upon the vibratory carrier and operative to advance the strip relative to the rollers, and driving means for imparting to the tensioning rollers peripheral speed greater than that of the snubbing rollers and to the strip feeding device a speed 15 substantially equal to the peripheral speed of the snubbing rollers and for vibrating the carrier in timed sequence with the operation of the rollers and feeding device.

17. A strip severing apparatus, including a strip feeding device, a strip tensioning roller, a strip snubbing roller, a vibratory mount common to the snubbing and tensioning rollers, power means for imparting to the tensioning and snubbing rollers differential peripheral speed by which 20 the tensioning roller speed exceeds that of the snubbing roller, and actuating means for vibrating the roll mount to effect intermittent engagement of the tensioning and snubbing rollers with the strip simultaneously and for actuating the 25 strip feeding device to advance the strip at a speed substantially equal to the peripheral speed of the snubbing roller.

18. A strip severing apparatus, including a strip tensioning device and a snubbing device intermittently engageable with a continuous strip simultaneously to subject the strip to longitudinal pulling strain in excess of a transverse weakened division line of the strip and to simultaneously resist such pulling strain, a strip feeding 40 device for continuously advancing the strip relative to the tensioning and snubbing devices, a vibratory control member common to the tensioning and snubbing devices for effecting intermittent timed engagement thereof with the strip, and driving means for operating the several devices in timed sequence.

JOHN T. DAVIDSON.
